UNITED STATES PATENT OFFICE.

THOMAS A. CONLON, OF SILVER SPRING, MARYLAND.

SEMITAUTOMATIC RAMMER FOR GUNS.

Application filed November 19, 1927. Serial No. 234,502.

(GRANTED UNDER THE ACT OF MARCH 3, 1883, AS AMENDED APRIL 30, 1928; 370 O. G. 757.)

The invention described herein, may be manufactured and used by or for the Government for governmental purposes without the payment to me of any royalty thereon.

5 This invention relates to a semi-automatic rammer for guns and is particularly adapted for guns whose length of recoil is less than the length of the round of ammunition.

In firing guns at aerial targets the gun is usually pointed at a considerable elevation and because of the weight of the round and the desirability of securing rapid fire during the brief interval that the target is within range it is advisable to employ a mechanical apparatus for ramming the rounds into the chamber.

In guns having a long recoil the rammer may be conveniently energized by the gun on recoil and held in cocked position as the gun 10 returns into battery. However, with guns of short recoil if the rammer is to be energized by the gun it must be so associated therewith that it will be moved an additional distance to the rear to allow for the excess 15 length of the round. In order to provide for this excess movement the present invention contemplates a rammer including a series of telescoping pistons designed to provide a ramming stroke which is three times 20 the stroke of the energizing member.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing 25 from the spirit of the invention.

40 A practical embodiment of the invention is illustrated in the accompanying drawings, wherein:

45 Fig. 1 is a view in side elevation and partly in section of a gun equipped with the improved rammer shown in the cocked or retracted position;

Fig. 2 is an enlarged longitudinal sectional view of the rammer in the position shown in Fig. 1;

50 Fig. 3 is a similar view of the rammer in the forward position;

Fig. 4 is a section on the line 4—4 of Fig. 1;

55 Fig. 5 is a sectional view of the rammer proper;

Fig. 6 is a longitudinal sectional view of a modified form of rammer shown in the forward position;

Fig. 7 is a plan view of the same showing the elements in the retracted position;

Fig. 8 is an enlarged sectional view of the buffer;

Fig. 9 is a detail sectional view on the line 9—9 of Fig. 3.

Referring to the drawings by numerals 65 of reference:

The ramming apparatus forming the subject of this invention is particularly adapted for rapid fire guns having breech mechanisms of the semi-automatic type and for 70 the purpose of illustration there is shown a gun of this character consisting of a barrel 5 reciprocally mounted in the cradle 6 and having a short recoil stroke considerably less than the length of the cartridge. The 75 gun, as shown, is provided with a vertically sliding or drop breech block 7 adapted to automatically open during the final counter recoil stroke of the gun in a well known manner to permit extraction of the empty 80 cartridge case. The breech ring of the gun is also formed with the usual loading recess 5^a incident to the use of the drop block and attached to the breech ring is a projectile tray 8.

85 The ramming apparatus as illustrated in Figs. 1 to 3 comprises a stationary cylinder 9 fixed to the cradle, a hollow piston or plunger 10 mounted therein and a piston 11 telescoping in the hollow piston. The piston 11 constitutes the rammer and carries at its rear extremity a round engaging finger 12 whose design is dependent on the character of the mounting employed. As shown the finger 12, is mounted in a housing 13 and is 90 normally depressed by a spring 14 to a position where it will engage behind the base of a cartridge placed on the tray, preparatory to being loaded into the chamber. For the purpose of eliminating vibration during 95 movement the housing 13 is formed with a T head 15 which is slidably fitted into a correspondingly grooved guide rail 16 secured to the cradle.

100 The hollow piston 10 is formed at its rear end with an annular seat 17 arranged to engage behind the gun lug 5^b and be retracted thereby on recoil. During such retraction a pressure fluid in the fixed cylinder 9 is displaced and caused to enter the hollow piston 110

through the ports 18. As the pressure increases the oil acting on the head 11^a of the piston 11 causes it to be retracted thereby energizing a reaction means, conveniently 5 air confined between the piston head and the rear wall 10^a of the hollow piston.

With the cross-sectional area of the piston 10 equal to one-half the area of the fixed cylinder 9 the piston 11 is moved to the rear 10 a distance equal to twice the displacement of the hollow piston 10 and this is increased to three times the length of recoil because of the bodily displacement of the piston 10. As a result a gun recoil of 16 inches imparts 15 a rammer stroke of 48 inches.

When the rammer has arrived at its rear-most position it is held cocked by means of a latch mechanism 19 mounted in the guide rail 16 and engaging in front of the T 20 head 15.

Inasmuch as the rammer must be returned to battery with sufficient force to release the extractors (not shown) which hold the breech block open it is desirable to place 25 the air behind the piston under an initial pressure and to employ a braking mechanism which, for example, may assume the form of a simple buffer 20 carried at the forward end of the fixed cylinder 9.

30 Where the characteristics of the gun are such as not to require the compact device just described, a rammer, operating according to the same principles, may be constructed as shown in Figs. 3 and 4. In this case 35 the outer cylinder 9^b instead of being fixed to the cradle is connected to the gun lug 5^b by means of rods 21 so as to be retracted by the gun and the hollow piston 10^b is fixed to the cradle 6 so that the pressure actuating fluid in the cylinder 9^b may directly 40 cause retraction of the rammer piston 11^b and compress air in the manner described.

While the ramming apparatus has been 45 shown as associated with a loading tray fixed to the cradle of the gun it is to be clearly understood that it may equally as well be mounted in an oscillating loading tray.

I claim:

50 1. In a loading apparatus for guns, a fixed outer cylinder, a recoil-actuated hollow piston spaced therefrom to form a fluid chamber and having fluid communication therewith, a piston in said hollow piston forming therewith a fluid chamber, a fluid under initial pressure in said chamber, a round engaging member associated with the piston, a latch for holding the pistons in extended position and means for checking 55 the momentum of the pistons upon restoration.

60 2. In a loading apparatus for guns, a fixed outer cylinder, a recoil-actuated hollow piston spaced therefrom to form a fluid

chamber and having fluid communication therewith, a piston in said hollow piston forming therewith a fluid chamber, a fluid under initial pressure in said chamber, a round engaging member associated with the latter piston, and a latch for holding the pistons in extended position. 65

3. In a loading apparatus for guns, a fixed outer cylinder, a recoil-actuated hollow piston spaced therefrom to form a fluid chamber and having fluid communication therewith, a piston in said hollow piston forming therewith a fluid chamber, a fluid in said chamber, a round engaging member associated with the latter piston, and a latch for holding the pistons in extended position. 75

4. In a loading apparatus for guns, a fixed outer cylinder, a recoil-actuated hollow piston spaced therefrom to form a fluid chamber and having fluid communication therewith, a rammer piston in said hollow piston forming therewith a chamber, a reaction element in said chamber, and means for holding the pistons in extended position. 85

5. A loading apparatus for guns, a fixed outer cylinder, a recoil-actuated hollow piston therein, a fluid displaceable into said hollow piston upon relative movement of the cylinder and hollow piston, a rammer piston in said hollow piston retractable by the displaced fluid, and a reaction element 95 energized upon retraction of said rammer piston. 90

6. In a loading apparatus for guns, a fixed outer cylinder, a recoil actuated hollow piston therein, a pressure fluid actuated rammer piston retractable on recoil movement of the hollow piston, and reaction means energized upon retraction of said rammer piston. 100

7. In a loading apparatus, a member movable in recoil with a gun, a pressure fluid retractable piston carried by said member and actuated during recoil movement of said member and reaction means energized by said piston. 105

8. In a loading apparatus, a member movable in recoil with a gun, a pressure fluid actuated piston retractable during recoil movement of said member and reaction means energized by said piston. 110

9. In a loading apparatus, a pair of telescoping pistons, one of which is recoil actuated and the other pressure fluid actuated and reaction means energized by the fluid actuated piston. 115

10. In a loading apparatus, a fluid actuated piston and a fluid compressing mechanism actuated by means of a gun in recoil and acting differentially to impart a movement to the piston in excess of the movement of the mechanism. 125

THOS. A. CONLON.
